F. J. BRYANT

LADDER

Original Filed July 5, 1918

Frederic J. Bryant
Inventor
By his Attorney *J. Parker*

UNITED STATES PATENT OFFICE.

FREDERIC J. BRYANT, OF NEW YORK, N. Y.

LADDER.

Original application filed July 5, 1918, Serial No. 243,328. Patent No. 1,406,972, dated February 21, 1922.
 Divided and this application filed June 9, 1921. Serial No. 476,213.

To all whom it may concern:

Be it known that I, FREDERIC J. BRYANT, a citizen of the United States, and resident of the borough of Manhattan, in the city, ⁵ county, and State of New York, have invented certain new and useful Improvements in Ladders, of which the following is a specification.

This invention relates to ladders, the subject matter of the present application, which is a division of my earlier application, Serial No. 243,328, filed July 5, 1918, since matured into Patent No. 1,406,972, dated February 21, 1922, being directed to ¹⁰ certain novel means employed in the construction of chain ladders, whereby in case one stile or chain should break away from its upper engaging means while the ladder is carrying a load, the tendency which normally exists for the rungs to strip off the other chain or stile is obviated, thereby preventing a possibly serious accident such as would result to a person using the ladder when the stripping action occurs. ¹⁵

Therefore my invention consists in the provision of a topmost rung for the ladder, upon which rung, near the opposite ends thereof, there are secured disks of relatively large diameter, disposed at the outer sides ²⁰ of the respective chains, so that if one chain should break loose from its upper fastening means, causing the entire load to be suddenly imposed upon the other chain, the shock and strain forces would not be exerted strip- ²⁵ pingly at the point of connection between the chain and rung, but will instead be absorbed by the disk, while the strain exerted by the upper chain length will continue to be directed in a line perpendicular to the rung axis. ³⁰

Other features and advantages of my invention will hereinafter appear.

In the drawing:

Figure 1 is an elevation showing a portion ⁴⁵ of a ladder, with upper fastening means, and with one fastening broken to illustrate the effect of the anti-stripping means.

Fig. 2 is an enlarged, sectional detail, ⁵⁰ showing a rung with an anti-stripping disk and securing means therefor.

Fig. 3 is a detail view of a thimble reinforcement of a link forming part of the upper engaging means for a ladder chain, and

Fig. 4 is a section on the line 4—4 of 55 Fig. 1.

In the example of my invention presented herewith, it is shown as applied to a ladder composed of the chain stiles 1, with wooden rungs 2 (one of these rungs only appearing in the fragmentary view of Fig. 1), which engage at their opposite ends with links of the respective chains. The topmost rung 3, however, is preferably composed of a metallic tube, that it may possess ample strength to, with certain adjunctive elements, (hereinafter described), lend itself to the anti-stripping feature of my conception. The tube 3 is of sufficiently small diameter so that it will enter a chain link (see Fig. 4) to effect union between the rung and ladder. Upon the rung 3, at each end thereof, outside the chain, I place a disk 4, whose diameter considerably exceeds that of rung 3, and exteriorly of disk 4 I place a nut 5 upon the rung, whose end is exteriorly threaded for the purpose. The rung end, where it affords a seat for the disk 4 and nut 5, may be reduced, to thereby provide an inner shoulder or bearing for said disk. Also, when the disk 4 and nut 5 have been fitted on the metallic tube comprising the rung, the end of said tube is upset, as at 6, to augment the security afforded by the nut against removal of the disk. ⁸⁵

The chain is localized in its position upon rung 3, and held against lateral movement thereon, by means of a spring clip 7, of inverted U-shape, which tensionally grips the rung and is provided with an outer groove to form a saddle or seat for the side bars of a rung engaging chain link. ⁹⁰

Each stile or chain engages by an end link 8 with a ring 9, that is to be suitably secured as by lashing 10 to a beam 11 or other form of upper anchorage. In the construction of the chain ladder shown in this application as the example wherewith my present invention is illustrated (which ladder in its more general constructive features is treated of in my said earlier application Serial No. 243,328), my purpose ¹⁰⁰

has been to combine the qualities of light weight, strength, and serviceability. The strength of the ladder is intended to be uniform throughout, without weak spots 5 that might cause a rupture. In following out this scheme of uniform strength the link 8 is seated in a thimble 12 that is of sufficiently rigid character to prevent said link 8 from distortion which might lead to 10 rupture.

It is only with respect to the means whereby the ladder is secured to its upper anchorage that liability of rupture exists, and, as will be apparent from the foregoing 15 disclosure, my invention is especially devised for the purpose of preventing the occurrence of possibly fatal accidents in the event of the ladder breaking away from the anchorage fastenings for one of its stiles.

20 Variations within the spirit and scope of my invention are equally comprehended herein.

I claim:-

1. A ladder including a pair of rung-
25 supporting chains and rungs carried by links thereof, characterized in that a metallic rung near the top of the ladder has its ends engageably entered within opposite links of the chains, and is provided 30 with bearing members respectively outside each chain, the diameter of said bearing members greatly exceeding the diameter of

the rung, and the inner surface of a bearing member co-acting with its adjacent chain to prevent chain stripping shock and strain 35 forces from being exerted directly at a rung end in the event of support breakage or disengagement under a load.

2. In a ladder having rungs and a pair of engaging chains therefor, the combination of an upper metallic rung and an externally grooved U-shaped member tensionally engaging said rung near each end thereof, said members respectively forming localizing saddles for the side bars of chain 45 links with which said rung engages.

3. The combination, in a ladder composed of chain stiles with rungs engaging them, of a topmost rung composed of metallic material, a grooved U-shaped saddle member tensionally fitted upon each end portion of the rung to seat and localize a rung engaging chain link, a bearing disk of much greater diameter than the rung, fitted upon said rung against the outer side 55 of each chain, a nut screwed upon the rung end to engage the disk, and the rung end being upset to secure the engagement of the assembled elements.

Signed at the borough of Manhattan, in 60 the city, county, and State of New York, this 27th day of April, A. D. 1921.

FREDERIC J. BRYANT.
